UNITED STATES PATENT OFFICE.

ELIZABETH BLICKENSDERFER, OF BRECKENRIDGE, COLORADO.

LAP-ROBE HOLDER FOR VEHICLES.

SPECIFICATION forming part of Letters Patent No. 763,459, dated June 28, 1904.

Application filed March 23, 1904. Serial No. 199,641. (No model.)

To all whom it may concern:

Be it known that I, ELIZABETH BLICKENSDERFER, a citizen of the United States, residing at Breckenridge, in the county of Summit 5 and State of Colorado, have invented new and useful Improvements in Lap-Robe Holders for Vehicles, of which the following is a specification.

My invention pertains to lap-robe holders 10 for vehicles; and its novelty, utility, and practical advantages will be fully understood from the following description and claim, when taken in connection with the accompanying drawings, forming part of this specification, 15 in which—

Figure 1 is a perspective view illustrative of a vehicle-seat equipped with three of my novel devices, the two outer devices being shown as holding a lap-robe. Fig. 2 is an enlarged detail section illustrating one of the 20 devices as connected to a vehicle-seat and holding a lap-robe. Fig. 3 is a plan view of the spring of the clasp as said spring appears precedent to being bent into U shape in longitudinal section. Fig. 4 is a plan view, partly broken away, of one of the devices.

Similar letters designate corresponding parts in all of the views of the drawings, referring to which—

A is a vehicle-seat having the usual cushion B, and C C C are my novel lap-robe holders. Three of the said holders are preferably employed, two being arranged adjacent to the ends of the seat for use when the same is occupied by two persons and one being arranged at the middle of the seat for use in conjunction with one end holder when but one person is on the seat. The holders are identical in construction, and therefore a detailed 35 description of the one shown in Figs. 2 to 4 will suffice to impart an understanding of all. Said holder comprises a looped strap a, connected, through the medium of nails b or other suitable means, to the seat A and extending 40 upwardly and forwardly over the cushion B, a slide c on said strap, and a clasp d, secured in the bight of the looped strap. As best shown in Figs. 2 and 3, the clasp d is made up of a flat lower jaw e, having an opening f 45 in its rear portion to receive the bight of the

strap a, a flat upper jaw g, and a spring h, disposed between the jaws e and g. The said spring is a flat spring, of steel or other suitable material, and has a body i approximately corresponding in width to the jaws e and g, 55 and reduced portions j extending in opposite directions from the body. It is of U shape in longitudinal section, and its end portions tend to normally rest against each other and to return to such position subsequent to an 60 opening of the clasp. Rivets k l are employed to connect the body and the end portions, respectively, of the spring to the jaws e and g, and from this it follows that the spring is calculated to lend strength to both of the jaws 65 as well as to connect the same and normally hold the forward ends thereof against each other and under considerable pressure. Because of both of the jaws e and g being flat and being connected through the medium of 70 a spring, such as described, it will be observed that when the clasp rests on the cushion B it will offer but a slight projection, and hence will not detract from the finished appearance of the vehicle-seat or be liable to render an 75 occupant thereof uncomfortable.

When two persons occupy the vehicle-seat, the two end holders are used after the manner illustrated in Fig. 1—i. e., the lap-robe is interposed between the lower and upper jaws 80 of the holder-clasps—while when but one person occupies the seat the robe will be held by the middle holder and one end holder. In either case it will be observed that the clasps will securely retain the lap-robe, and yet in 85 the event of accident the robe may be quickly and easily jerked from the clasps, this because the opposed faces of the forward portions of the clasp-jaws are plain or free from teeth. 90

As will be readily appreciated by reference to Fig. 1, my novel lap-robe holders are calculated, when the clasps thereof are nickel-plated or otherwise embellished, to enhance rather than detract from the finished appearance of a vehicle-seat. 95

Notwithstanding the practical advantages which I have ascribed to my novel holders, it will be noticed that the same are simple and inexpensive in construction and embrace no 100
